GRAF ALFRED VON SODEN-FRAUNHOFEN, OF FRIEDRICHSHAFEN, GERMANY, AS-SIGNOR, BY MESNE ASSIGNMENTS, TO ZAHNRADFABRIK GESELLSCHAFT, OF FRIEDRICHSHAFEN, GERMANY.

CHANGE-SPEED GEAR.

Application filed January 26, 1922. Serial No. 531,810.

To all whom it may concern:

Be it known that I, GRAF ALFRED VON SODEN-FRAUNHOFEN, a citizen of Germany, residing at Friedrichshafen a. B., Germany, 5 have invented certain new and useful Improvements in Change-Speed Gears, of which the following is a specification.

My invention relates to change speed gear for motor cars and particularly to such gear 10 in which the locking of the striker rods which are inoperative for the time being is effected by a rotary locking member common to all striker rods, this locking member substantially consisting of a cylinder having 15 perforations arranged in staggered relation and adapted to cooperate with locking pins fixed to the striker rods. Owing to this arrangement of perforations, only a single striker rod is free to move at a time, while 20 all other striker rods are locked against movement by their locking pins abutting against solid portions of the locking cylinder. The striker rod which shall be thrown in in each individual case is caused to advance 25 towards the cylinder by means of a spring provided for this purpose, its locking pin entering the perforation of the cylinder in front of it. The locking cylinder can be set either by hand or preferably by means 30 of a suitable setting device, well known per se, and which comprises a spring or springs adapted to be placed under different tensions, according to which the locking cylinder is rotated through a larger or smaller 35 angle, thus placing one or the other perforation in front of the locking pin appertaining to it.

It is an object of my invention to so arrange lock and unlock the striker rods as to 40 obtain a gear of very compact design. To this end the striker rods are partly moved in opposite directions when moving the sliding wheels into identical positions. The sliding wheels are for instance arranged in 45 pairs symmetrically with regard to a common central clutch member for each pair and must therefore be moved in opposite directions in order to engage and disengage them with the clutch. This opposite movement of the striker rods is rendered possible 50 by the striker rods engaging the locking

member from opposite sides. The simultaneous unlocking of all striker rods can be effected by aid of a yoke which is so designed that it unlocks in opposite direction 55 those striker rods which are operated in opposite direction.

A further means for effecting the operation of the striker rods in opposite directions is provided by reversing the motion of 60 part of the striker rods which are arranged all on side of the locking member by means of double armed levers, which are operated by the principal striker rods and in turn operate auxiliary striker rods which, however, do not engage the locking member but 65 merely serve to operate the sliding wheels. The simultaneous unlocking of all the rods is effected in the usual manner, for instance, by a bar extending transversely to the 70 striker rods. However, the auxiliary striker rods are not provided with catches for the unlocking bar so that the corresponding sliding wheels are moved only by aid of the double armed levers and therefore in opposite 75 direction. The auxiliary striker rods may, however, also be dispensed with and the sliding wheels may be operated directly by the double armed levers.

I prefer employing a hollow locking cylinder 80 provided with perforations disposed in staggered relation.

In the drawings affixed to this specification and forming part thereof two modifications of a device embodying my invention 85 are illustrated diagrammatically by way of example. In the drawings—

Fig. 1 is a section on line A—A in Fig. 2,

Fig. 2 is a plan view, and

Fig. 3 a section on line B—C in Fig. 2, a 90 locking cylinder being arranged to be engaged by three striker rods on one side and by two striker rods on the other,

Fig. 4 is a section of the second modification, taken on line D—D in Fig. 6, 95

Fig. 5 is a section on line E—E in Fig. 6, and

Fig. 6 is a plan view, with the locking cylinder in longitudinal section, of a gear, 100 all the striker rods being here arranged on the same side of a locking cylinder.

Referring first to Figs. 1 to 3, the striker

rods, 1, 2, 3 are arranged on the left and the striker rods 4 and 5 on the right hand side of the locking cylinder 6. The striker rods carry pins 1^a, 2^a, 3^a, 4^a, 5^a adapted to engage with perforations 6^a in the wall of the cylinder 6. The arms 1^b, 2^b, 3^b for operating the sliding wheels connected with the striker rods 1, 2 and 3, such as shown in Fig. 1 move from the left to the right, while 10 the arms 4^b and 5^b for the striker rods 4 and 5 move from the right to the left. All the striker rods are acted upon by springs 7 which move them into their locking positions. The unlocking is effected by means 15 of a strap 8 supported by two trunnions 9 and adapted to be turned about them with the aid of a lever arm 9^a mounted on one of the trunnions 9 and which is either operated by hand or is 20 connected with the general controlling mechanism of the car, thus causing the locking pins to be automatically withdrawn from the perforation in the locking cylinder, whenever or before a change of speed is effected. 25 The strap engages the striker rods 1, 2 and 3 by its body, the striker rods 4 and 5 by pins 10, 10. When the strap is turned about its trunnions 9, the striker rods 1, 2, 3 are moved to the left and are unlocked, while 30 the striker rods 4 and 5 are moved to the right and are unlocked also.

Referring now to Figs. 4 to 6, all the striker rods are here arranged on the same side of the locking cylinder. The reversal 35 of the motion of part of the striker rods is effected in this case by double armed levers. Thus the striker rod 12 is connected with an auxiliary striker rod 14 by a double armed lever 15 which is fulcrumed to the 40 frame of the gear. Striker rod 12 does not move sliding wheel 13 directly when it engages the corresponding recess in the locking cylinder 6, but merely releases the auxiliary rod 14 connected with the wheel 13 45 by an arm 14^b whereupon the spring 16 on the striker rod 14 moves the sliding wheel 13 and at the same time causes the striker rod 12 to engage its recess in the cylinder 6, the rod 12 being thus forced into 50 the respective recess of cylinder 6 by the action of the spring 16 and the lever 15. On the other hand striker rod 11 is acted upon directly by a spring 17 and actuates the respective wheel directly by aid of an 55 arm 18. The rods are unlocked by a bar 19 extending transversely to the striker rods and which can be turned about trunnions 20. The rods 11 and 12 carry lugs 11^c, 12^c, respectively, adapted to be engaged 60 by the bar 19, while the auxiliary rod 14 has no lug. On the bar 19 being operated, the rods 11 and 12 are withdrawn from the recesses in the locking cylinder 6, the movement of rod 12 being transmitted to the

auxiliary rod 14, by the double armed lever 65 15 so that the sliding wheel 13 apportioned to auxiliary rod 14 is moved in opposite direction to that of rod 12.

I wish it to be understood that I do not desire to be limited to the exact details of 70 construction shown and described, for obvious modifications will occur to a person skilled in the art.

I claim:

1. In a change speed gear in combination, 75 a plurality of sliding wheels, striker rods in operative connection with said wheels, means for moving said rods into and out of operative position and a common locking member for all said rods, the locking motion of part of said rods being effected 80 in a direction opposite to that of the other rods.

2. In a change speed gear in combination, 85 a plurality of sliding wheels, striker rods in operative connection with said wheels, means for moving said rods into and out of operative position and a common rotary locking member for all said rods, the locking motion of part of said rods being effect- 90 ed in a direction opposite to that of the other rods.

3. In a change speed gear in combination, 95 a plurality of sliding wheels, striker rods in operative connection with said wheels, means for moving said rods into and out of operative position and a common locking member for all said rods, part of said rods being disposed on one, another part on the opposite side of said locking member and the locking motion of said first mentioned rods being effected in a direction opposite to that of the other rods.

4. In a change speed gear in combination, 100 a plurality of sliding wheels, striker rods in operative connection with said wheels, means for moving said rods into operative position, a common locking member for all said rods, the locking motion of parts of 105 said rods being effected in a direction opposite to that of the other rods and means, common to all said rods, adapted to simultaneously unlock all said rods.

5. In a change speed gear in combination, 110 a plurality of sliding wheels, striker rods in operative connection with said wheels, means for moving said rods into operative position, a common locking member for all 115 said rods, the locking motion of parts of said rods being effected in a direction opposite to that of the other rods and a double armed lever adapted to simultaneously unlock all said rods.

6. In a change speed gear in combination, 120 a plurality of sliding wheels, striker rods in operative connection with said wheels, means for moving said rods into and out of operative position, a locking pin on each 125

rod, a locking cylinder having perforations disposed in staggered relation and in line with said locking pins, part of said rods being disposed on one side, part on the other side of said cylinder and a strap capable of rocking about a horizontal axis and adapted to cooperate with the rods on either side of said cylinder in displacing them in opposite directions so as to disengage said pins from said cylinder. 10

In testimony whereof I affix my signature.

GRAF ALFRED von SODEN-FRAUNHOFEN.
